UNITED STATES PATENT OFFICE.

HENRY DAMERELL, OF LUDLOW, MISSOURI, ASSIGNOR OF ONE-HALF TO
FRANK WAY, OF SAME PLACE.

REVERSING SLIDE-VALVE.

SPECIFICATION forming part of Letters Patent No. 628,396, dated July 4, 1899.

Application filed April 8, 1898. Serial No. 676,850. (No model.)

To all whom it may concern:

Be it known that I, HENRY DAMERELL, of Ludlow, in the county of Livingston and State of Missouri, have invented a new and useful Improvement in Reversing Slide-Valves, of which the following is a specification.

My invention relates to certain improvements in slide-valves for steam-engines; and it consists in the peculiar construction and arrangement of parts designed to provide a simple, practical, and efficient valve for reversing an engine, as will be hereinafter more fully described with reference to the drawings, in which—

15 Figure 1 is a longitudinal section through the cylinder, steam-chest valves, and its operating devices. Fig. 2 is a side view of the valve-shifting mechanism, with steam-chest in section. Fig. 2^a is an edge view of the lever n^2 p^2 . Fig. 3 shows the position of the parts of the valve after reversing.

In the drawings, X represents the steam-cylinder, O its piston, and Y the steam-chest. The steam-cylinder has the two induction-ports J J' and the intermediate exhaust-port K. Within the steam-chest, over the ports J, J', and K, slides the compound valve. This valve consists of a distributing-valve A and an independently-movable section W, interposed between the ports of the cylinder and the distributing-valve A. The distributing-valve A is independently adjusted by a stem H, and the slide-section W is provided with a sleeve R, by which it and valve A are reciprocated from the eccentric. The stem H passes concentrically through the sleeve R, the latter being provided with a stuffing-box a^2 at the point where said stem 30 H emerges from the steam-chest and the sleeve R being offset to one outside of the steam-chest (see Fig. 1) in the form of an arm R', while the central stem H, which is attached to the distributing-valve, extends straight through the offset, which is provided with a stuffing-box a^2 at the point where said stem 35 H emerges from the offset. This makes two independent connections outside the steam-chest for working the two parts of the compound valve together or separately, as hereinafter described.

40 The distributing-valve A has a large exhaust-chamber L in it opening inwardly in

the middle and also through ports l^2 near its ends. There are also formed in the inner side of valve A two induction-ports C C', which are located between the central exhaust-opening L in valve A and the end opening l and l' . These induction-ports C C' open into the steam-chest to admit steam through the passages D E F G into the ports J J' of the cylinder.

45 The distributing-valve rod H is jointed to a lever n^2 , fulcrumed at y^2 to a rocking arm p^2 , (see Figs. 2 and 2^a,) which at its lower end is hinged, as at s^2 , to a suitable fixed point. The bottom end of lever n^2 is jointed to a shifting rod s^3 , worked by lever s^4 . The upper end of arm p^2 is connected to eccentric-rod V², connected to an eccentric which rocks arm p^2 and causes the reciprocation of both parts of the valve W and A in the normal 60 working of the engine.

50 The operation is as follows: In the position shown in Fig. 1 live steam from the steam-chest enters opening C and passes, through E and port J, into the side n of the cylinder, 75 forcing the piston in the direction of the arrow, and the steam on the side m passes out J', through G to l' , and then through central exhaust L, through B, to exhaust K. When the rods R and H are together moved by the eccentric to the right, the valve A W shifts to the right and the port D is over J, F is over J', and live steam entering at C' passes through F to J' to the side m of the piston, forcing it in the other direction, and the steam on side 80 n passes out J, through D and l , to L and through B to the exhaust K. Now to reverse the motion of the engine, the relation of the distributing-valve A and slide-section W is changed through the agency of the rod H and 85 sleeve R, and for this purpose distributing-valve A is slid to the right on the part W, as shown in Fig. 3. This is effected through lever s^4 , rod s^3 , and lever n^2 , and as the upper end of n^2 in Fig. 2 is thrown to the right 90 it pulls rod H and distributing-valve A to the right on the intermediate part W. Now the two parts A and W of the valve reciprocate as before from the action of the eccentric, but with this difference in the arrangement of the 95 parts that C' is over G, which is an induction-port, D is exposed in the steam-chest and is 100

the other induction-port, C and l' are dead or 5
inoperative ports, and l' is over E and is an
exhaust-port. This, it will be seen, changes
ports D and G to live ports and ports F and
E to exhaust-ports, which changes the direc-
tion of the motion of the engine.

Having thus described my invention, what
I claim as new, and desire to secure by Letters
Patent, is—

- 10 1. The combination with a steam-cylinder
having a central exhaust and two end ports;
of a compound reversing-valve consisting of
a flat slide-section arranged to move on the
ports of the steam-cylinder, and having five
15 passages through it arranged as described,
a sleeve connecting with said slide-section
and emerging from the steam-chest through
a stuffing-box, a distributing-valve section
arranged to move directly upon the slide-sec-
20 tion and having central exhaust-chamber,
end exhaust-openings, and intermediate in-
duction-openings, said distributing-valve sec-
tion having also an attached rod extending

through the sleeve of the other valve-section
and having an independent external connec- 25
tion for adjusting it substantially as and for
the purpose described.

2. In a reversing-valve mechanism, the combi-
nation with the two parts of a compound
valve; of a sleeve attached to one part of the 30
valve and issuing from the valve-chest and
provided with an offset arm R' and a connect-
ing-rod and eccentric for working it, a lever
 p^2 connected at its upper end to said working
parts and fulcrumed to a stationary part be- 35
low, a concentric rod attached to the other
part of the compound valve and issuing from
the steam-chest through the sleeve, a lever n^2
jointed at its upper end to said rod, fulcrumed
at its middle to arm p^2 and connected at its 40
lower end to a rod and adjusting-lever sub-
stantially as and for the purpose described.

HENRY DAMERELL.
